United States Patent Office

Des. 188,121

Patented June 7, 1960

188,121

BUDGET BANK

Morton Bertisch, 2357 Army Place, Bellmore, N.Y.,
and Gerald Bertisch, 780 Rockaway Ave., Valley
Stream, N.Y.

Filed Aug. 19, 1959, Ser. No. 57,228

Term of patent 14 years

(Cl. D34—5)

FIG. 1.

FIG. 2.

Fig. 1 is a top perspective view of a budget bank embodying our new design and showing the same in closed position; and

Fig. 2 is a top perspective view thereof with the cover open, and with part of the front wall broken away.

The opposite sides not shown in the drawing, are substantially the same as the sides shown.

We claim:

The ornamental design for a budget bank, substantially as shown and described.
